his Attorney

UNITED STATES PATENT OFFICE.

JOHN K. CAMPBELL, OF LOS ANGELES, CALIFORNIA.

FOLDING-TABLE CABINET.

1,210,415.

Specification of Letters Patent. Patented Jan. 2, 1917.

Application filed March 30, 1916. Serial No. 37,675.

To all whom it may concern:

Be it known that I, JOHN K. CAMPBELL, a citizen of the United States, residing at Los Angeles, in the county of Los Angeles and State of California, have invented new and useful Improvements in Folding-Table Cabinets, of which the following is a specification.

This invention relates to cabinets, and particularly to folding table and shelf cabinets.

The invention contemplates an improved folding table cabinet, the table of which may be readily and easily swung out of the cabinet into position for use, or into the cabinet and out of sight, when not in use.

More particularly, the invention comprises an improved brace for bracing the table in position for use, which brace is automatically brought into bracing position as the table is swung down into position for use, and automatically moved out of bracing position and folded up with the table when the table is folded up in the cabinet out of use.

Other important improvements of the invention will appear hereinafter.

The invention is illustrated in the accompanying drawings, which form a part of this specification, in which:

Figure 1 is a front view of the invention with the table folded up within the cabinet out of use. Fig. 2 is a vertical section of the invention taken on line $\alpha^2-\alpha^2$ of Fig. 1, with the table and other parts thereof folded up within the cabinet. Fig. 3 is a perspective view of the invention with the table swung down and out of the cabinet and braced in position for use; other parts of the apparatus remaining within the cabinet. Fig. 4 is a view similar to Fig. 2 except that the table and ironing board are swung down and out of the cabinet and are braced in position for use. Fig. 5 is a perspective view of the sleeve board. Fig. 6 is a perspective view of a portion of the table brace. Fig. 7 is a perspective view of the bracket supports for extension leaves of the table. Fig. 8 is a detail sectional view of the end of the table showing how the table leaf supporting brackets are held in folded position out of use. Fig. 9 is a detail vertical sectional view of the table and one of its leaves, showing the dowel pin for holding the leaf in alignment with the main member of the table and the lock engaging said pin and locking the leaf to the main table member. Fig. 10 is a detail horizontal sectional view of the parts shown in Fig. 9 taken on line $\omega^{10}-\omega^{10}$ of said figure. Fig. 11 is a detail perspective view of a portion of the cabinet illustrating means for holding the table leaves properly in position within the cabinet. Fig. 12 is an enlarged detail vertical sectional view of the cabinet base member and the table brace hinged to said base member; the brace being shown in folded position out of use in full lines and in bracing position in dotted lines.

The invention may comprise a cabinet 1, a table 2, a brace 3 for the table, ironing board 4 and sleeve board 5. The table 2 is hinged by hinge 6 to cross bar 7 secured within the cabinet. The pivot of the hinge 6 is in front of the bar 7 and the front of the bar is within the cabinet so that the table may be folded within the cabinet as shown in Fig. 2. The brace 3 is formed in two members 9 and 10, which are hinged respectively, by hinges 11 and 12 to cabinet base member 13 and the table 2, and are held together in sliding relation by angle iron 15, one flange 16 of said angle iron being secured to the side edges of the legs 17 at the lower end of brace member 10 and the other flange 18 thereof engaging the face of the brace member 9, (Fig. 6). The pivot of the hinge 11 rests above the upper edge of the cabinet base member 13 so that the legs 17 at the lower end of brace member 10 may engage the upper edge of said base member in notches 21 therein, whereby the table 2 is braced in position for use by the brace member 10, as shown in Figs. 3, 4 and 12. Side extensions 25 are provided on the upper end of brace member 9, which extensions are engaged by angle iron flange 18 and rest against legs 17 of brace member 10, when the table is folded up in the cabinet, as shown in Fig. 2, in which position of the parts an opening 26 is formed between the legs 17 and the extensions 25 to permit access to a shelf 27 in the cabinet. A door 30 is hinged to the lower edge of the brace member 10 which normally closes the opening 26. A catch 31 holds the table 2 in its folded position within the cabinet. To the under side of the table is secured a transverse member 32, to the ends of which are hinged brackets 33 which brackets are adapted to be swung outwardly into the position shown in Fig. 3 to support one end of the

table leaves 35, the other end of said leaves being adapted to be received between brackets 36 and strips 37 secured to the front of the cabinet 1 and rigidly supported in horizontal position by said brackets and strips, as illustrated in Fig. 3. The table 2 is provided with recesses 40 in its side edges to receive dowel pins 41 projecting from the side edges of the table leaves 35 when the leaves are placed in position at the sides of the table 2 to extend the table, as illustrated in Figs. 9 and 10, whereby the table members are held in alinement. Locks 45 pivoted at 46 to the under side of the table 2 have pins 47, which project through slots 48 in the table and are adapted to engage notches 49 in the dowel pins 41 to lock the table members together in alinement. Catches 50 are provided under the table 2 for engaging and holding the folding brackets 33 in folded position. A brace 51 braces the member 33 on the table and said member may be used as a shelf when the table is folded up within the cabinet, as shown in Figs. 1 and 2.

25 The ironing board 4 is hinged by hinge 55 to the upper front edge of cross bar 7, so that the board may be folded up within the cabinet behind the table 2, when not in use, and swung down upon the table, the board 30 being provided with a foot 56 adapted to rest on the table near the front end thereof to support the front end of the board so that the board will rest in horizontal position for use. A catch 57 is provided for 35 holding the board in its folded position within the cabinet.

A curtain 60 is mounted in the upper front part of the cabinet which may be let down to hide the interior of the cabinet 40 and give the cabinet a neat appearance, when the table and ironing board are swung out of the cabinet as shown in Fig. 4.

The table leaves 35 are adapted to rest in the rear of the cabinet upon cross member 7 between blocks 61 and behind ironing board 4 when said board is folded within the cabinet as illustrated in Fig. 2. Catches 62 in the upper rear portion of the cabinet are adapted to engage notches in the upper 50 ends of said leaves to prevent said leaves swinging down and out of the cabinet when the table and ironing board are let down into position for use, as illustrated in Fig. 4. The front and upper surfaces of the blocks 55 61 are beveled so as to guide the leaves between the blocks when said leaves are placed within the cabinet. The blocks 61 and catches 62 hold the leaves 35 rigidly in position within the cabinet.

60 To the under side of the sleeve board 5 at the rear end thereof is secured a base member 65, which is adapted to rest upon the rear end of the ironing board 4 and support the sleeve board slightly above the 65 ironing board, and a cleat 66 is secured to

the rear of the sleeve board, which cleat is adapted to extend down over the rear edge of the ironing board and engage the under surface of the ironing board, whereby the sleeve board is held properly in position on 70 the ironing board for use when the ironing board and table are swung down, as shown in Fig. 4. The sleeve board is provided with a hole 70 through which a pin 71 in the upper rear portion of the cabinet is 75 adapted to project to hang up the sleeve board within the cabinet as shown in Figs. 2 and 3.

A door 75 is hinged to the upper portion of the cabinet which is adapted when closed 80 to hide the upper end of the ironing board so as to give the upper part of the cabinet a neat finish. The door is held closed by a catch 76. The door is provided with a recess 77 into which the ironing board foot 85 56 is adapted to project, when the ironing board is folded up in the cabinet, so that the door may be closed.

When the parts are all in the cabinet as shown in Fig. 1 and the door 75 is closed, 90 said door, table 2, brace members 10 and 9 and door 30 are all of such design as to give the entire front of the cabinet a neat appearance.

In order to swing the table into position 95 for use, it is only necessary to disengage the catch 31 and swing the table down on the hinges 6 into horizontal position during which movement of the table, the brace member 10 slides down automatically on 100 the brace member 9 until the legs 17 of the brace member engage the upper edge of the cabinet base member 13 in notches 21, whereby the table is automatically arrested and braced in horizontal position for use. 105

In order to extend the table, the catch 50 is released from the brackets 33 and the brackets swung outwardly; the catches 62 are released from the leaves 35 and the leaves removed from the cabinet are slipped over the brackets 33 and 36 and under strip 37 until the dowel pins 41 project into the recesses 40 and the latch pins 48 automatically engage the notches 49 in the dowel pins and lock the table members together in 110 alinement.

In order to bring the ironing board into position for use, it is only necessary to disengage the catch 57 and swing the board down on the hinge 55 until the foot 56 rests 115 upon the front end of the table.

In order to place the sleeve board into position for use it is only necessary to take the board off the pin 71 and place the board on the rear of the ironing board with the 120 cleat 66 in engagement with the under side of the ironing board.

In order to place the parts within the cabinet, the sleeve board 5 is first slipped off the rear end of the ironing board and 125 130

hung up on the pin 71 in the upper portion of the cabinet; the latches 45 are then pressed so that the pins 47 disengage the dowel notches 49 and the leaves 35 are slipped sidewise off the brackets 33 and 36 and from under strip 37 and placed within the cabinet between blocks 61 and in engagement with catches 62; the ironing board 4 is folded up on hinges 55 within the cabinet and engaged and held in such position by catch 57; the brackets 33 are then folded up on member 32 and held by catch 50 in such position; and the table is then folded up on hinge 6 within the cabinet until engaged and held by catch 81, during which folding movement of the table, the brace member 10 slides upwardly on brace member 9 and automatically extends itself to accommodate the position of the table.

I claim:

1. In a folding table cabinet, a table hinged within the cabinet, a brace comprising upper and lower brace members hinged respectively to said table and the cabinet base, legs on said upper brace member, extensions on said lower base member registering with said legs when the brace is extended, said brace being adapted to swing on its hinges as the table is swung out of or into the cabinet, said upper brace member being adapted to slide upon the lower brace member as the table is let down until said legs engage said base to brace the table in position for use, a shelf in the cabinet, a door hinged to the lower end of the upper brace member and covering the space between said legs, said brace members forming a closure for the cabinet when said door is in front of the space above said shelf when the table is folded within the cabinet.
2. In a folding table cabinet, a table hinged within the cabinet to swing in a vertical plane, a table brace comprising upper and lower brace members arranged in slidable relation to each other, the upper member being hinged to said table and the lower member to the cabinet base, legs on said upper member, extensions on said lower member, said brace being adapted to swing in a vertical plane on its hinges as the table is swung out of or into the cabinet, the upper member being adapted to slide upon the lower member as the table is let down until the legs of said upper member engage said base to brace the table in position for use, a vertically swinging door hinged to the lower end of said upper member and covering the space between said legs, said members forming a closure for the cabinet when the table is folded within the cabinet, and means for locking said table in vertical position.
3. In a folding table cabinet, a table hinged within the cabinet and adapted to swing in a vertical plane, a flat brace comprising upper and lower members arranged in slidable relation to each other, said upper member being hinged to said table, and said lower member to the cabinet base, a recess in the lower end of said upper brace member, said brace being adapted to swing on its hinges when the table is swung out of or into the cabinet, said upper member being adapted to slide upon said lower member as the table is let down to engage said base to brace the table in position for use, a door covering said recess on said upper member, said brace members forming a closure for the cabinet when the table is folded within the cabinet, and means for locking said table in folded position.
4. In a folding table cabinet, a table hinged within the cabinet, a flat brace comprising upper and lower members arranged in slidable relation to each other, the upper member being hinged to said table and the lower member being hinged to the cabinet base, said brace being adapted to swing on its hinges as the table is swung out of or into the cabinet, the upper brace member being adapted to slide upon the lower brace member as the table is let down, until it engages said base to brace the table in position for use, said brace members forming a closure for the cabinet when said table is folded within the cabinet, and means for locking said table in folded position.
5. In a folding table cabinet, a table hinged within the cabinet and swinging in a vertical plane, a brace comprising upper and lower brace members arranged in slidable relation to each other and hinged respectively to said table and to the cabinet base, a pair of brackets arranged on opposite sides of the hinged end of the table, a bracket arranged on the under side of the free end of said table, said last named bracket comprising a pair of hinged end members adapted to swing in a horizontal plane and to project laterally on opposite sides of said table to form supports for a pair of table leaves, a pair of loose table leaves adapted to form lateral extensions of said table and to rest upon said brackets, and manually operated locking means mounted on said table for locking said leaves in position.
6. In a folding table cabinet, a table hinged within the cabinet and swinging in a vertical plane, a brace comprising upper and lower brace members arranged in slidable relation to each other and hinged respectively to said table and to the cabinet base, a pair of fixed brackets arranged on opposite sides of the hinged end of the table, a bracket arranged on the under side of the free end of said table, said last named bracket comprising a pair of hinged end members adapted to swing in a horizontal plane and to project laterally on opposite sides of said table to form supports for a pair of table leaves, a pair of loose table leaves adapted to form lateral extensions of said table and to rest upon said brackets, and manually operated locking means mounted on said table for locking said leaves in position.
7. In a folding table cabinet, a table hinged within the cabinet and adapted to swing in a vertical plane, a flat brace comprising upper and lower members arranged in slidable relation to each other, said upper member being hinged to said table, and said lower member to the cabinet base, a recess in the lower end of said upper brace member, said brace being adapted to swing on its hinges when the table is swung out of or into the cabinet, said upper member being adapted to slide upon said lower member as the table is let down to engage said base to brace the table in position for use, a door covering said recess on said upper member, said brace members forming a closure for the cabinet when the table is folded within the cabinet, and means for locking said table in folded position.

4
plane and to project laterally on opposite sides of said table to form supports for a pair of table leaves, a catch on the under side of said table for holding said hinged end members when the latter are in inoperative position, a pair of loose table leaves adapted to form lateral extensions of said

table and to rest upon said brackets, and manually operated locking means mounted on said table for locking said leaves in position.

In testimony whereof I have signed my name to this specification.

JOHN K. CAMPBELL.
